(57) **CLAIM**

The ornamental design for an electronic copying machine, as shown and described.

DESCRIPTION

FIG. 1 is a top, front and left side perspective view of an electronic copying machine showing our new design;

FIG. 2 is a front elevation view thereof;

FIG. 3 is a top elevation view thereof;

FIG. 4 is a rear elevation view thereof;

FIG. 5 is a bottom elevation view thereof;

FIG. 6 is a left side elevation view thereof;

FIG. 7 is right side elevation view thereof; and,

FIG. 8 is a top, front and left side perspective view showing the state in which the electronic copying machine is used in combination with a sheet feeder and a stacker.

The broken line showing of a sheet feeder and stacker in FIG. 8 is for illustrative purposes only and forms no part of the claimed design.
